UNITED STATES PATENT OFFICE.

SUNKER ABAJI BISEY, OF NEW YORK, N. Y.

NOZZLE MECHANISM.

Application filed October 30, 1920. Serial No. 420,654.

To all whom it may concern:

Be it known that I, SUNKER ABAJI BISEY, a subject of the King of Great Britain, and a resident of New York, county and State of New York, have invented certain new and useful Improvements in Nozzle Mechanisms, of which the following is a specification.

My present invention relates to type casting machines and particularly to the nozzle construction thereof.

The objects of the invention are to provide simple and effective mechanism for conducting the molten metal in a direct line from the metal pot to the mold chamber, practically without obstructing the flow and in such a way as to insure complete charging of the mold chamber under flow pressure.

Another important object is to prevent chilling of the metal in the end of the nozzle by contact with the relatively cooler mold.

A further object is to make the nozzle construction adaptable to the various adjustments of the type casting mold.

These objects I have accomplished by novel construction and arrangement of parts, certain embodiments of which are disclosed in the accompanying drawing, in connection with which I wish it understood that the same is illustrative in character, inasmuch as various other changes and modifications may be made without departure from the true spirit and scope of the invention as hereinafter defined and claimed.

In the drawing referred to:

Figure 1 is a vertical sectional view of an improved type mold equipped with my improvements, the parts being shown in the casting or mold charging position.

Figure 2 is a fragmentary view of the same parts shown in the position they assume after the cast is made.

Figures 3 and 4 are fragmentary sectional views of slightly modified forms of the invention.

The invention of the present application is, for the most part, a division from my application Serial No. 164,199 in which the mold structure is particularly disclosed and broadly claimed. For that reason, it is only necessary in the present application to state that the mold shown consists of upper and lower mold blocks 5 and 6 spaced to provide a mold chamber and each carrying a side wall member projecting from one mold

block toward the other, so as to define a mold chamber 7 which is adjustable as to size because of the adjustable relation of the two mold blocks and the side wall forming members carried thereby. At the back, the mold chamber is closed by upper and lower plates 8 and 9 relatively adjustable to provide a mold gate 10 and at the front the chamber is closed by the matrix 11 which is shown as carried by a slide 12 operated by the cam actuated lever 13.

The metal pot which may be of any usual or desirable construction is indicated in a fragmentary way at 14. This pot is shown as provided with an adjustable nozzle carrying boss 15 having a throat or passage 16 and vertically adjustable to fit the gate of the mold by being supported in guides 17, on the wall of the pot, and shiftable by means of an adjusting screw indicated at 18.

This adjustable nozzle support is provided with a bore or guide passage 19 extending toward the mold and slidably receiving the nozzle 20. This nozzle has a metal passage 21 to register with the throat 16 and a longitudinal passage 22 in which the choker or cut-off valve 23 reciprocates in such a way as to open or close the metal outlet at the end of the nozzle.

At the end of the nozzle and interposed between the same and the back of the mold chamber is a nipple plate 24 having a rounded or concave seat 25 receiving the similarly rounded ends of the nozzle and choker. This nipple plate further has a flaring metal outlet 26 to register with the mold gate 10.

The nipple plate may be supported in various ways. In Figures 1 and 2 I have shown the same as yieldingly and rockably guided and supported at the end of the nozzle by guide studs 27 and springs 28, the nipple plate having guide openings 29 loosely receiving said studs and the springs being interposed between the nipple plate and the back of the mold so as to normally force the nipple plate away from the mold surfaces. This outward movement of the nipple plate is limited in the present disclosure by the nuts 30 adjustably engaged on the outer threaded ends of the studs.

In the operation of the parts thus far described, when a cast is to be made, the nozzle and choker in the relation indicated in Figure 2, are advanced to press the nipple plate firmly against the back or gate wall of

the mold chamber. Just before the piston of the metal pot forces the metal up through the throat, the choker is withdrawn sufficiently to clear the mouth of the nozzle, as shown in Figure 1, and the metal is thereupon forced directly into the mold. Immediately the cast is made, the choker is advanced to close the port in the nozzle so as to cut off the metal and prevent any metal remaining in the nozzle end. The nozzle with the choker in this position is then retracted, enabling the springs 28 to react and separate the nipple plate from the mold surface.

15 This prevents the nipple plate and nozzle from cooling by continued contact with the mold surface and enables the port 26 in the nipple plate to clear the jet on the end of the casting, as indicated in Figure 2. The described movements of the nozzle and choker may be effected by suitable cams operating on the levers 31 and 32 which are shown as adjustably connected with the nozzle and choker respectively by the pin and slot connections, indicated at 33 and 34.

20 A spring 35 is also indicated as operating on the choker to hold the same normally advanced in position, closing the inclined passage in the nozzle and the port in the nipple plate. The nipple plate is shown as having a beveled or conical forward portion 36 seating loosely in a correspondingly shaped recess 37 at the back wall of the mold.

25 The construction shown in Figure 3 is similar to the one described, except for the fact that the nozzle which is here designated 38 is not retracted, but remains at all times in engagement with the nipple plate 39, which latter also remains in contact with the mold wall. In this construction it is simply necessary to reciprocate the choker, the lever 32 which performs this function being shown in this instance as extending 30 within the upper part of the metal pot, as does also the choker, which enables any metal in the choker passage draining back 35 into the pot.

30 In the construction illustrated in Figure 4, the choker or cut-off valve is in the form of a sliding plate 40 which reciprocates vertically in between the back wall of the mold and the nipple plate 41. This sliding choker has a port 42 to register with the mold gate and with the ports in the nipple plate and in the end of the nozzle 43. After a cast is made with this form of the invention, the choker plate 40 is lowered into the dotted line position indicated to carry the 35 port 42 therein down into register with a knock-out plunger 44 which is actuated by a reciprocating lever 45 to eject the slug 46 from the port 42. This construction possesses certain of the advantages of the other 40 forms described, and has certain additional

advantages as will be apparent to those skilled in the art.

What I claim is:

1. The combination with a type casting mold provided with a mold chamber having a gate opening in one wall thereof, of a metal charging nozzle, a nipple plate movably interposed between said nozzle and the gate wall of the mold chamber, and means for reciprocating the nozzle with respect to the nipple plate. 70
2. The combination with a type casting mold provided with a mold chamber having a gate opening in one wall thereof, of a metal charging nozzle, and a nipple plate movably interposed between said nozzle and the gate wall of the mold chamber, said nipple plate having a beveled projection and the mold having a correspondingly shaped seat receiving the same. 75
3. In a machine of the character described, a mold having a gate opening in one wall thereof, a metal charging nozzle having a bore in line with the gate opening and inclined throat leading to said bore, a choker reciprocating in said bore, and a nipple plate interposed between the nozzle and gate wall of the mold and provided with a port in line with the gate opening. 80
4. In a machine of the character described, a mold having a gate opening in one wall thereof, a metal charging nozzle having a bore in line with the gate opening and inclined throat leading to said bore, a choker reciprocating in said bore, a nipple plate interposed between the nozzle and gate wall of the mold and provided with a port in line with the gate opening, and means for advancing the nozzle and choker to press the nipple plate in engagement with the mold wall and for then retracting said parts to free the nipple plate from contact with the mold wall. 85
5. In a machine of the character described, a mold having a gate opening in one wall thereof, a metal charging nozzle having a bore in line with the gate opening and inclined throat leading to said bore, a choker reciprocating in said bore, a nipple plate interposed between the nozzle and gate wall of the mold and provided with a port in line with the gate opening, and means for advancing the nozzle and choker to press the nipple plate in engagement with the mold wall and for then retracting said parts to free the nipple plate from contact with the mold wall. 90
6. In a machine of the character described, a mold having a gate opening in one wall thereof, an adjustably mounted metal charging nozzle, and a universally adjustable nipple plate interposed between the nozzle and the gate wall of the mold. 95
7. In a machine of the character described, 100

130

a mold having a gate opening in one wall thereof, a metal charging nozzle reciprocable toward and away from the gate wall, a nipple plate interposed between the end of said nozzle and said gate wall, said nipple plate being yieldably supported to advance toward the gate wall when engaged by the nozzle, a choker reciprocating in the nozzle, means for bodily adjusting the nozzle and choker with respect to the mold, and actuating means for the nozzle and choker operative irrespective of the adjustments of said parts.

8. In a machine of the character described, a mold having a gate opening in one wall thereof, a nozzle reciprocable toward and away from said gate opening, a choker reciprocating in said nozzle, means for bodily adjusting the nozzle and choker, and actuating means for the nozzle and choker operative irrespective of the adjustments thereof.

9. In a machine of the character described, a mold having a gate opening in one wall thereof, a nozzle reciprocable toward and away from said gate opening, a choker reciprocating in said nozzle, means for bodily adjusting the nozzle and choker, actuating means for the nozzle and choker operative irrespective of the adjustments thereof, a nipple plate interposed between the end of the nozzle and the gate wall of the mold, and supporting means enabling adjustment of said nipple plate to the nozzle and choker.

10. In a machine of the character described, a reciprocating metal charging nozzle provided with a metal passage, a choker reciprocating in said nozzle and controlling said passage, means for operating said nozzle and choker, and an adjustable support for the nozzle and choker, the operating means aforesaid being operative irrespective of the adjustments of said support.

11. In a machine of the character described, a mold having a gate opening in one wall thereof, a metal charging nozzle, a nipple plate interposed between the end of said nozzle and the gate wall, studs loosely supporting the nipple plate in this position, and spring means for yieldingly holding the nipple plate engaged with the nozzle. 45 50

12. In a machine of the character described, a mold having a gate opening in one wall thereof, a metal charging nozzle, a nipple plate interposed between the end of said nozzle and the gate wall, studs loosely supporting the nipple plate in this position, spring means for yieldingly holding the nipple plate engaged with the nozzle, and adjustable stop means limiting the motion of the nipple plate. 55 60

13. In a machine of the character described, in combination, a nozzle, a cooperating nipple plate, a choker sliding in the nozzle, and operating means for forcing the nozzle, choker and nipple plate toward the mold preliminary to casting and for retracting the choker during the casting operation and for advancing the choker when the cast is completed and for then retracting the nozzle, choker and nipple plate to disengage the nipple plate from contact with the mold surface. 65 70

14. In a machine of the character described, a mold, a nozzle having a metal passage, a choker sliding in the nozzle and controlling the metal passage, means for retracting the choker to open the metal passage during mold charging operations, and means for bodily adjusting the nozzle with respect to the mold. 75 80

In witness whereof, I have hereunto set my hand this 27th day of October, 1920.

SUNKER ABAJI BISEY.
